ARCH CRADLE SHOE CONSTRUCTION

Nathan Hack, 537 San Vincente Blvd., Santa Monica, Calif., assignor of one-third each to Morton Hack and Leonard Hack, both of Detroit, Mich.

Filed Nov. 27, 1959, Ser. No. 855,827

7 Claims. (Cl. 36—8.5)

This invention relates to an arch cradle shoe construction and more particularly to an arch cradle having a band portion disposed transversely of the shoe and suspended above the insole upon lateral flanges or extensions secured to the side walls of the shoe below the plane of the band portion.

The invention involves a band strip of resilient, cushioning, supporting material, in its basic form, disposed transversely of the shoe and above the insole within the area of the longitudinal inner and outer arches of the foot and rearward of the transverse arch. The band strip is arranged in three sections which include the middle arch cradle in the open area of the shoe to receive the foot arch, and the two side extensions or flanges at the ends thereof which are secured to the shoe side walls. It is highly desirable but not absolutely necessary that the band strip have an elastic property or characteristic so that as the foot bends and flexes in and with the shoe, the arch cradle is in constant supporting contact with the foot. A modified form of the band strip provides for a T-arrangement wherein a stem connected to the transverse arch cradle portion extends rearwardly to the rear heel wall and is there secured in supporting relationship to the heel.

It is an object of the invention to provide an arch cradle for the foot mounted on the side walls of a shoe by flanges or extensions secured below the plane of the arch cradle. Another object is the provision of such an arch cradle having an elastic characteristic permitting the cradle to constantly move with the foot arch in supporting relationship thereto. A further object is to provide an arch cradle with a rearward extension secured to the rear heel wall whereby additional resilient support is provided for the heel.

These and additional objects of the invention and features of construction will become more clearly apparent in the description given below, in which the terms used are employed for purposes of description and not of limitation.

Reference is here made to the drawing annexed hereto, made an integral part of this specification, and in which

Fig. 1 is a perspective view of a shoe embodying the inventive arch cradle construction.

Fig. 2 is an enlarged vertical transverse sectional view substantially on the line 2—2 of Fig. 1.

Fig. 2a is a view substantially identical to Fig. 2, except showing the securing of the band strip extensions in a slightly different arrangement.

Fig. 3 is another view similar to Fig. 2, showing yet another arrangement for securing the band strip extensions in a shoe having no side wall counter.

Fig. 4 is a perspective view of a shoe embodying a modified arch cradle construction.

Fig. 5 is an enlarged vertical longitudinal sectional view substantially on the line 5—5 of Fig. 4.

As shown particularly in Figs. 1 and 2 of the drawing, the shoe 10 comprises an upper 12, an insole 14, a counter 16 mounted in side walls 18, 18 of the upper, and

2

conventional soling 20 and heel 22. Secured transversely of the shoe and above the plane of the insole 14 is an arch cradle band strip 24 having an arch cradle portion 26 and extensions or flanges 28, 28 at each end thereof.

5 The arch cradle strip 24 is positioned within the area of the longitudinal arches of the foot, rearwardly of the transverse arch, in order to provide additional or required support to the arch. This area, as shown in the several views in the drawing and particularly in Figs. 1, 4 and 5, is that area in and adjacent the heel breast line. The transverse strip 24 is arranged with its flanges 28, 28 disposed through slotted openings 30, 30 in the side wall lining 32 in a downwardly direction and below the plane of the arch cradle portion 26, where the flanges are secured to the counter 16 by stitching 34. Although not shown the flanges 28, 28 may extend into the area under the side edges of the insole 14, should additional securing be desired or required.

The arch cradle band strip 24 has the function of 20 providing resilient, cushioning, and supporting assistance to the longitudinal inner and outer arches of the foot. It is therefore desirable to embody in the strip 24 such features as resiliency and longitudinal and transverse strength by way of its materials. An elastic band having 25 resilient rubber or plastic threads interwoven with textile or fabric threads appears to have many of the desirable properties required. A soft resilient leather or leather-like material may be employed. It is possible that synthetic yarns and woven materials or nonwoven materials 30 will furnish the necessary resilient, cushioning and supporting characteristics here described. An operative material is a closely woven cotton fabric elastic band having rubber fibers or threads interwoven in the fabric of the band.

35 As is shown in Fig. 2a, the arch cradle band strip 24 is secured to the side walls 18, 18 by stitching 34 passed through the side wall, the counter 16, the flange 28, and the lining 32 at each end of the arch cradle portion 26 therebelow. This construction permits the application of the arch cradle concept in shoes which are already fabricated. The slotted opening 30 is cut into the lining 32 and the arch cradle flange 28 introduced therethrough to a position below the plane of the arch cradle portion 26. When in this position the stitching is 45 then applied.

Where a shoe is constructed without a counter, as in Fig. 3, the arch cradle flanges 28, 28 are secured by stitching 34 to the lining 32 and by a suitable adhesive 36 to the inside surface 38 of the side walls 18, 18.

50 It will be observed in viewing Figs. 2, 2a and 3 that the arch cradle band strip flanges 28, 28 are substantially vertically arranged in the nature of piers to support each end of the arch cradle portion 26. Such disposition of the elements is a more proper functional arrangement. In the prior art, attempts to provide support for the arch were made by securing the arch cradle to the side walls above the plane of the arch cradle portion, or to the lacing strips of the upper, or by enwrapping the foot in the area of the arches and then supporting 55 the wrapper at the lacing. Such constructions are considered inefficient or unworkable in that one merely encases the foot without supporting it. To properly support the arch of the foot, the upbearing must come from below and be founded upon the shoe structure below the plane of the arch cradle portion. This is the construction and function of the instant invention.

Another advantage of the inventive construction here disclosed is that the arch cradle portion 26 adapts itself to every contour of the foot arch without requiring any special design. The arch cradle tends to resist rolling 70 over of the foot by providing side elements in the arch cradle portion 26, when the foot is in the shoe, above

the plane of the foot arch that tend to oppose rotation of the foot, thus achieving a balancing corrective effect for persons having this tendency.

The arch cradling strip of material embodies a feather-weight foot balancing feature that stabilizes the foot within the shoe without crowding the foot as when an arch supporting element is inserted into the shoe.

A further advantage of the arch cradle construction is to elevate the transverse arch rearward of the metatarsal heads so that pivoting of the foot in walking or running is improved. The described arch cradle band strip supports the foot in a hammock, bridging fashion, and stabilizes the foot while standing or walking. The construction heretofore disclosed embodies an economical structure that can be built into substantially 90% of current production shoes for men, women and for youngsters' growing feet.

A modification of the basic arch cradle construction is that illustrated in Figs. 4 and 5, wherein the shoe 10 is provided with an arch cradle band strip 50 having a transverse arch cradle portion 52, extensions or flanges 54, 54 at the ends thereof, and a stem portion 56 running longitudinally of the shoe toward the heel wall 58, substantially medially from the center of the portion 52, and having an extension or flange 60 at the end thereof. The transverse arch cradle flanges 54, 54 are secured as above described for the arch cradle band strip 26. The stem portion 56, as shown in Fig. 5, is disposed through the opening 62 in the lining 32, the flange 60 being arranged downwardly below the plane of the opening 62 and secured by stitching 34 to the counter 16. The end of the stem portion 56 adjacent the lining 32 is elevated above the plane of the transverse arch cradle portion 52, to provide more support for the foot and to further assist in elevating the arch. Of course, the various arrangements for securing the flanges of the strip 26 are also applicable for securing flanges 54, 54 and 60 of the strip 50, and it is to be understood that these arrangements and combinations of the strip 50 and the shoe upper 12 are embodied as described above.

It is desirable to fabricate the arch cradle band strip 50 in a single piece, in order that the foot arch and heel be most comfortably seated in the shoe, however the stem portion 56 may be produced separately from the transverse arch cradle portion 52 and secured thereto by sewing or other suitable means well known in the art to which the invention pertains.

Having described the invention in its simplest terms, it is to be understood that the details of construction may be changed and varied in greater or lesser degree without departing from the essence of the invention defined in the appended claims.

I claim:

1. In an arch supporting shoe, an upper structure, an arch cradle band strip having an arch cradle portion disposed in a horizontal and substantially parallel plane above the insole of said shoe in the area of the heel breast line, said band strip having flanges extending downwardly of the plane of said arch cradle portion and secured in said upper structure, whereby said arch cradle portion is bridged between sides of said upper structure.
2. In an arch supporting shoe, an upper structure, an arch cradle band strip having an arch cradle portion disposed in a horizontal and substantially parallel plane above the insole of said shoe in the area of the heel breast line, said band strip having flanges extending downwardly of the plane of said arch cradle portion and secured to said upper structure, whereby said arch cradle portion is a bridge supported on said upper structure.
3. The structure defined in claim 2, and in which said upper structure is provided with a counter, said flanges being secured to said counter.
4. The structure defined in claim 2, and in which said upper structure is provided with an outer wall and a lining for said outer wall, said flanges being disposed between said outer wall and said lining and secured to said lining.
5. The structure defined in claim 2, and in which said flanges are secured to said upper structure by stitching passed through said upper structure and said flanges.
6. In an arch supporting shoe, an upper structure, an arch cradle band strip having a principal arch cradle portion and a connecting stem portion secured normal to said arch cradle portion rearwardly thereof, said arch cradle and stem portions being secured to said upper structure above the plane of the insole of said shoe and in the area of the heel breast line, said cradle portion and said stem portion having flanges extending downwardly of the plane thereof and secured to said upper structure, whereby said arch cradle portion is a bridge supported on said upper structure.
7. The structure defined in claim 6, and in which said upper structure is provided with a counter, said flanges being secured to said counter.
